WALL PAPER HANGING, PASTING, AND TRIMMING DEVICE

Richard M. Smith, Gastonia, N. C.

Application April 13, 1956, Serial No. 577,986

4 Claims. (Cl. 216—6)

This invention relates to a device for hanging, pasting, and trimming wall paper, and more particularly has reference to a device of this nature which may be summarized briefly as follows:

The device includes a shallow frame of U-shaped cross section intermediate opposite ends of which there is provided means for rotatably supporting a roll of wall paper. At one end of the frame, there is provided a receptacle for paste, and rotating in said receptacle is a paste applicator in roller form, traversed by the wall paper as it unrolls. Guide means are provided upon the frame, adapted to lead the wall paper to the opposite end of the frame after paste has been applied thereto, and at said opposite ends of the frame there is provided roller means adjustable transversely of the frame, and serving the function of the conventional brush by means of which paper is pasted onto a wall.

The construction is adapted to permit substitution of a brush for the last-named roller means, and above the roller means there is provided a trimmer, shiftable transversely of the frame for the purpose of trimming the paper at the ceiling and baseboard of a wall. Further, associated with one of the guide members of the apparatus is a selvage trimming blade means, usable either for trimming selvage from the roll or alternatively, for pre-trimming a strip of paper to fit in a confined area under certain circumstances.

The main object of the present invention is to provide a generally improved device of the nature referred to that can be applied with maximum ease and facility for the purpose of applying paste to the paper, applying the paper to a wall or ceiling surface, trimming the paper at the sides thereof, and trimming the ends of the applied paper at the ceiling and baseboard.

Another object of the invention is to provide means on the device readily adjustable for the purpose of accommodating rolls of different widths, thus increasing measurably the versatility of the device.

Still another object is to so design the apparatus as to permit its manufacture at low cost, while still producing a rugged, efficient device for the purposes stated.

Yet another object is to provide apparatus that will fill the many desirable aims set forth above, and will at the same time be very light, easy to handle, and usable in almost all situations that may be encountered during the operation of hanging wall paper.

Other objects will appear from the following description, the claims appended thereto, and from the annexed drawings in which like reference characters designate like parts throughout the several views and wherein:

Figure 1 is a side elevational view of a paper hanging, pasting, and trimming device formed according to the present invention;

Figure 2 is a top plan view in which the paper has been shown in dotted lines;

Figure 3 is a longitudinal section on line 3—3 of Figure 2;

2

Figure 4 is an enlarged transverse sectional view, portions being broken away, on line 4—4 of Figure 3;

Figure 5 is an enlarged, detail sectional view on line 5—5 of Figure 3; and

5 Figure 6 is a perspective view of an auxiliary brush that may be employed according to the desires of the particular user in place of the roller means shown in Figures 1—3.

Referring to the drawings in detail, designated generally by the reference numeral 10 is a rectangular frame, 10 open at top and bottom, said frame including elongated, flat parallel side frame members 12, 12. The side frame members are disposed in vertical planes, during the normal usage of the apparatus, and fixedly connected between the forward ends of the side frame members is a cross bar 14 which, as shown in Figure 3, is of substantially triangular section, tapering in a direction forwardly from the frame when viewed in cross section.

In the tapered, forward portion of the cross bar 14 there is formed a dovetail groove 16, extending the full length of the cross bar, and opening upon the opposite ends of the cross bar. A roller means is removably carried by the cross bar 14, and includes a support bar 18, having a dovetail tongue mating with the groove 16 as shown in Figure 3. The support bar 18 extends substantially the full width of the frame, and as will be understood, can be engaged in the dovetail groove by extension through one end of the dovetail groove.

Due to this arrangement, the roller means carried by support bar 18 can be adjusted bodily in a transverse direction upon the frame, for the purpose of permitting slippage thereof from side to side so that the roller included in said roller means may be offset to either side of the frame, to permit papering around a window or door frame.

35 In selected positions to which the cross bar 18 is adjusted transversely of the frame, it frictionally engages the cross bar so as to be retained in the desired position.

On opposite ends of the cross bar, there are formed forwardly projecting arms 22, and extending between and 40 journaled at its ends upon the arms is a front roller 24, the core of which is covered with sponge rubber. Slots 27, the purpose of which will be made apparent hereinafter, are formed in the respective arms 22.

It will be seen that the cross bar 18, and the components carried thereby, constitute an applicator means whereby the wall paper W, unrolled from a roll R of wall paper, and having paste applied thereto in a manner to be described hereinafter, is pressed firmly against the wall, and is applied smoothly thereto in the desired area responsive to movement of the frame the length of the area to be covered. In this connection, the frame can be grasped at opposite sides thereof by the hands of the user. Alternatively, suitable handle means, not shown, may be incorporated therein according to the desires of the particular manufacturer.

To this end, the frame and all other metal parts of the device, would be light weight metal to facilitate handling, the convenient and easy handling of the apparatus being of course a matter of great importance.

60 Overlying the applicator means is an end trimming means, including elongated, straight arms 26 having their inner ends secured fixedly to the inner surfaces of the forward end portions of the side frame members 12. The arms are extended forwardly above the roller means, 65 inclining upwardly from the frame, and connected between the ends of the arms is a slotted cross member 28 (Figure 3). Slidably engaged in the slot of the cross member 28, which slot extends the full length of the cross member and has been designated at 30, is a trimming blade 32, having an upwardly projecting knob providing a handle. When the paper has been applied to the wall or ceiling, the blade 32 is used to trim the pa-

70

per at the ends thereof. One need only apply the trimming blade 32 against the paper at the location at which it is to be cut, after which the blade 32 is shifted from one to the other end of the slot 30 to cut the paper.

Intermediate the ends of the frame, there are provided paper guides spaced longitudinally of and extending transversely of the frame. The guides are identical, so the description of one will suffice for both.

Each guide includes upwardly projecting support arms or standards 34, extending above the top edges of the side frame members 12, and connected between the upper extremities of the support members 34 are closely spaced, straight, small diameter guide bars 36, 38. Mounted upon the upper guide bar 36 are spacer collars 40, 40, these being spaced axially of the guide bar 36 as shown to best advantage in Figure 2. Since the wall paper W travels through the guides with its pasted side up, the collars 40 serve the purpose of preventing dragging of said pasty side against the cross bar 36.

Mounted upon the transversely extending guide bar 36 is a selvage trimming blade including a collar 42 having a set screw for securing the same in selected positions to which it is axially adjusted along the length of the guide bar. Fixed to the collar 42 is a depending, triangular blade 44, the cutting edge of which is inclined from the vertical and faced rearwardly as shown in Figure 3, in the direction from which the paper is issuing.

As the paper travels between the guides, a selvage strip S (Figure 2) may be cut therefrom by the blade 44. It will be understood that more than one selvage or trimming blade 44 can be provided upon its associated guide, so as to trim selvage from both sides of the wall paper if necessary. These trimming blades are adjustable axially of the guide bar 36, independently of one another, so as to be disposed at selected distances apart, along the length of the guide bar 36.

For the purpose of supporting the roll R upon the frame, there is provided an elongated shaft 46 having circumferentially grooved end portions 48 engaging in angular slots 49 formed in the respective side frame members 12.

Mounted upon shaft 46 are spaced, confronting discs or heads 50, 52. Disc 52 is secured to shaft 46 against axial movement therealong at one end of shaft 46, so that roll R in every instance will be disposed at one end of the shaft adjacent one side of frame 10. Disc 50 is adjustable axially of the shaft, into engagement with the opposite end of the roll, so as to permit rolls of different widths to be accommodated in the apparatus.

Mounted upon the rear end of the frame is a means for applying paste to the unpatterned face of the wall paper W, said means being combined with a rear end guide, about which the wall paper is led prior to passage thereof to the front end of the frame.

The paste applying and guide means are carried by the frame as a joint assembly capable of being bodily rotated about an axis extending transversely of the frame, for a purpose to be made presently apparent. Adjacent each member 12, there is provided a support arm 54, connected intermediate its ends to a pivot pin 56 (see Figure 4) carried by the adjacent member 12, a spacer sleeve 58 being interposed between said arm 54 and members 12. Depending from arms 54 at the lower ends of said arms is an upwardly opening, trough shaped paste container 60, connected to arms 54 for pivotal swinging movement about an axis paralleling that defined by pins 56. Container 60 is so connected to arms 54 by an elongated roller shaft 62, carrying a paste applicator roller that includes a hard core 64 about which is circumscribed a thick sponge rubber sleeve 66, enclosed within a relatively thin covering 68 of a material impervious to the passage of paste therethrough, the covering 68 being corrugated from end to end thereof. In a preferred embodiment it is anticipated that the surface of the covering 68 will have approximately eight corrugations to the

inch, but this number may be varied according to the desires of the particular manufacturer.

Formed upon the container, along one side thereof (Figure 3) is an inwardly directed longitudinal flange 70 to which is secured a resiliently flexible wiper strip 72 extending into contact with the applicator roller to wipe excess paste therefrom.

In the upper ends of arms 54 there are formed short, closed longitudinal slots 74 receiving the ends of a guide roller shaft 76 carrying a guide roller 78, resiliently biased toward the applicator roller by the contractile springs 80 connected between spacer sleeves 58 and the ends of shaft 76.

Paper as manufactured is rolled in either of two ways, from the bottom of the pattern to the top or vice versa. The drawing illustrates paper that unrolls from the bottom of the wall to the top and under these circumstances the paste container, applicator roller, and guide roller 78 are positioned as shown. For paper that unrolls from the top of the wall to the bottom, the device is bodily inverted. Under these circumstances, arms 54 rotate 180 degrees about pins 56. This rotates the container, applicator, and guide roller as a unit until they are once again in the position shown in Figure 1, with the frame being inverted as mentioned above. The wall paper will still follow the same line illustrated in Figure 1 under these circumstances.

In use of the device, the paper unrolling from roll R passes between the guide roller 78 and the applicator roller means 64, 66, 68. The paper rotates these rollers, so that a uniform coating of paste is applied to the paper. The paper then passes about roller 78, and between the spaced guide bars 36, 38, as shown in Figure 1. Then, the paper passes about the roller 24, which is pressed against the wall, not shown, so that the paper will be properly hung upon the wall.

In the event that the paper is being hung in a space too small to accommodate the roller 24, a brush having bristles of a length to approximately two inches is mounted adjacent the roller 24. Said brush is illustrated in Figure 6, and comprises an elongated, wide, flat support bar 82 the opposite ends of which are formed with depending arms 84 terminating at their lower ends in outwardly projecting, rectangular lugs 86 engaging in slots 27 of arms 22. Bristles 88 project forwardly from and are embedded in bar 82.

While the paper is traveling from one to the opposite end of the frame, the selvage may be trimmed therefrom by proper placement of blade or blades 44.

Further, when the ends of the applied paper must be cut, the end trimming blade 32 is employed in the manner previously described herein.

The purpose of blades 44, primarily, is to trim the selvage. However, these blades have the secondary purpose of pretrimming a strip of paper to fit the same into a relatively small space such as one existing between two window frames.

It may be further noted that one of the discs 50, 52, or both of them, may be calibrated or otherwise marked on its face to indicate when a predetermined amount of paper is left upon the roll.

It is believed apparent that the invention is not necessarily confined to the specific use or uses thereof described above, since it may be utilized for any purpose to which it may be suited. Nor is the invention to be necessarily limited to the specific construction illustrated and described, since such construction is only intended to be illustrative of the principles it being considered that the invention comprehends any minor change in construction that may be permitted within the scope of the appended claims.

What is claimed is:

1. A wall paper hanging device comprising: a frame adapted for rotatably supporting a roll of paper; means at one end of the frame for applying paste to said paper

following unrolling therefrom from said roll; guide means spaced longitudinally of the frame for guiding the paper from said one end to the other end of the frame; and means at the opposite end of the frame for applying the paper to a surface to be covered thereby, said last named means being mounted upon the frame for adjustment in a direction transversely of the frame.

2. A wall paper hanging device comprising: a frame adapted for rotatably supporting a roll of paper; means at one end of the frame for applying paste to said paper following unrolling therefrom from said roll; guide means spaced longitudinally of the frame for guiding the paper from said one end to the other end of the frame; and means at the opposite end of the frame for applying the paper to a surface to be covered thereby, said last named means being mounted upon the frame for adjustment in a direction transversely of the frame, and including a U-shaped yoke having a dovetail tongue, the frame being formed with a transversely extending dovetail groove slidably receiving said tongue.

3. A wall paper hanging device comprising: a frame adapted for rotatably supporting a roll of paper; means at one end of the frame for applying paste to said paper following unrolling therefrom from said roll; guide means spaced longitudinally of the frame for guiding the paper from said one end to the other end of the frame; and means at the opposite end of the frame for applying the paper to a surface to be covered thereby, said last named means being mounted upon the frame for adjustment in a direction transversely of the frame, and including a U-

25

shaped yoke having a dovetail tongue, the frame being formed with a transversely extending dovetail groove slidably receiving said tongue, said last named means further including a roller carried by the arms of said yoke.

4. A wall paper hanging device comprising: a frame adapted for rotatably supporting a roll of paper; means at one end of the frame for applying paste to said paper following unrolling therefrom from said roll; guide means spaced longitudinally of the frame for guiding the paper from said one end to the other end of the frame; and means at the opposite end of the frame for applying the paper to a surface to be covered thereby, said last named means being mounted upon the frame for adjustment in a direction transversely of the frame, and including a U-shaped yoke having a dovetail tongue, the frame being formed with a transversely extending dovetail groove slidably receiving said tongue, said last named means further including an elongated brush having bristles projecting forwardly from the frame, said brush being adapted at opposite ends thereof for removable engagement with the arms of the yoke.
